UNITED STATES PATENT OFFICE.

NUCHIM LEIB WEINGOTT, OF WARSAW, RUSSIA.

TELEPHONE AND STATION APPARATUS.

No. 879,073.

Specification of Letters Patent.

Patented Feb. 11, 1908.

Application filed December 30, 1907. Serial No. 408,690.

To all whom it may concern:

Be it known that I, NUCHIM LEIB WEINGOTT, mechanician, citizen of Russia, subject of the Emperor of Russia, residing at Warsaw, in the Kingdom of Poland and Empire of Russia, have invented certain new and useful Improvements in Telephones and Station Apparatus, of which the following is a full, clear, and exact description.

10 The present invention relates to a device, to extend and to facilitate the use of telephonic wire plants in towns and so on.

The fundamental idea of the invention is to replace the usual stationary telephones by portable pocket-telephones. Junction points, at which pocket-telephones are inserted into the telephonic wire plant must be provided as many as possible in the whole town, in establishments etc., at suitable places 20 easily accessible to public use, so that the owner of a pocket-telephone will have no difficulties whatsoever to connect the same with the wire-plant.

Portable telephones are already known; 25 however the same have been used up to the present time only by a limited number of partakers, as for instance by the officials of railway companies, by the visitors of large hotels and of other establishments, in short 30 for purposes, whereby a payment for the use of the telephonic wire plant was not raised. The portable telephones up to now in use have the disadvantage of not rendering possible a control for the purpose of raising 35 money for the use of the wire plant. This is also the reason, why the portable telephones known up to the present time have not found any general application.

The present invention renders it possible 40 to compel the owner of a pocket-telephone to make regular, as for instance annual payments to the telephone companies for the use of the wire plant. This aim is arrived at by the peculiar formation of the contact-device, 45 by means of which the pocket telephone is connected with the telephonic wire plant. The pocket telephones carry keys, which are attached to them by means of short conductors and which fit into stationary junction-pieces provided in the wire-plant. 50 These keys are provided with contacts corresponding to the contacts in stationary junction-pieces. Whenever the contacts of the junction-pieces are changed, the keys 55 can make no more contact therewith. Consequently the owner of the pocket-telephone

must exchange his key for a new key in the telephonic wire plant, whereby he will have to pay a new rent for the further use of the telephonic wire plant.

60 The question is to be able to easily transpose and change the contact of the stationary junction-device, as well as to easily exchange the contact key of the pocket telephone for a new one.

65 Further it is necessary for the sake of introduction of the invention into general use to form the portable telephone as compact as possible, for instance in the shape of a watch.

In the accompanying drawings: Figure 1 70 is a perspective view of a pocket telephone and station box. Fig. 2 is a perspective view of the modified form of pocket telephone in open position. Fig. 3 is a perspective view of the same in closed position. 75 Fig. 4 is a central axial sectional view of the telephone shown in Fig. 1. Fig. 5 is a rear elevation of the telephone shown in Fig. 4. Figs. 6, 7 and 8 are sectional views of details 80 of the telephone connections. Fig. 9 is a transverse sectional view of a telephone showing a modified form of connection. Fig. 10 is an axial sectional view of the telephone shown in Fig. 9. Fig. 11 is a rear elevation of the mechanism of the station apparatus. Fig. 12 is a side elevation of the same. Figs. 13, 14, 15 and 16 are detail 85 views partly in section of the devices for connecting the telephone and the station apparatus. Fig. 17 is a side elevation of a modified form of the mechanism of the station apparatus. Fig. 18 is a rear elevation 90 of the apparatus shown in Fig. 17. Fig. 19 is a horizontal sectional view of a portion of the apparatus shown in Figs. 17 and 18. 95 Fig. 20 is a side elevation of another modified form of the mechanism of the station apparatus. Fig. 21 is a plan view of the mechanism shown in Fig. 20.

In Fig. 17 designates the casing of the 100 stationary junction-piece. Such casings are conveniently provided at different easily accessible places of the town, as for instance in the vestibules of hotels, of ware houses, of restaurants and so on.

105 6 is an opening in the lid of the casing into which the conductor 4 of the pocket telephone 1, 2, 3 is inserted by means of the contact 5 formed like a key.

110 In the watch-like casing 3 there are united the receiver and the transmitter. On the visible perforated side of 3 the transmitter

is arranged and on the back is the receiver, from which the sound is conducted through the hearing tube 1 to the ear of the speaker. The hearing tube 1 is fastened to the casing 3 in such a way, that it can be detached by being drawn out.

12 is the diaphragm before which the suitably formed end of the receiver is pushed by means of the guides 11.

10 The union of the transmitter and receiver in the casing 3 is represented by Fig. 4. The cable 4 comprises four insulated conducting wires, which are introduced from below into the casing. The casing 3 comprises in the 15 one half the receiver with the microphone 15 consisting of a stratum of coal-dust; two of the four wires belong to the receiver, the other two wires belong to the transmitter. Here the flat form of the electromagnet 14 20 may be particularly pointed out.

In Figs. 6-8 the connection of the cable 4 with the casing 3 is represented. The connection is arranged in such a way, that the cable 4 can be conveniently and quickly 25 changed, which every time must be done, as soon as the contacts of the stationary junction-pieces are to be changed for the purpose 30 of raising new payments for the use of the telephonic wire plant at the end of a subscription period. The casing 3 is provided below with a shell 16 firmly screwed on. Into this shell there is inserted an insulation-body 17, provided with four holes, which are provided with lateral excavations 21. Into the 35 four holes there enter the extremities 20 of the wires, that lead to the receiver and to the transmitter. The wire-extremities 20 are formed like needles with curvatures corresponding to the excavations 21. These 40 curvatures prevent any longitudinal displacement of the extremities 20 in the insulating piece 17. The extremities somewhat protrude out of the part 17. The insulating piece 18 carries four metal tubes 22, in which 45 the extremities of the four wires of the cable 4 end. When the insulation-piece 18 is inserted into the shell 16, the needle-like shaped extremities 20 enter into the tubes 22 and complete the connection of the casing 50 3 with the cable 4 *i. e.* with the key 5. The insulation piece 18 is fastened within the shell by means of the screws 19.

When at the end of the subscription period the key 5 must be exchanged, the screws 19 55 need only to be loosened in order to replace the cable 4 with the key 5 by another cable with a new key.

Another form of the pocket-telephone is represented by Figs. 2, 3, 9 and 10. According to the same the receiver and the transmitter are arranged in two separate narrow casings 8 and 10, which can be shut by being put together (Fig. 3) and opened by being drawn asunder (Fig. 2) by means of the intermediate piece 9 formed as in spectacles.

In the position shown by Fig. 2 the telephone is represented as it is used; the position shown by Fig. 3 represents the state of the telephone as carried in the pocket; the cable in this arrangement may consist of two wires 70 only, that are led to the transmitter 10 and along the intermediate parts 9 to the receiver.

Figs. 9 and 10 represent the exchangeable connection between the cable 4 and the transmitter 10. The same has the shape of 75 a watch-bow 23, 24. The one wire is connected with the bow 23 and by this with the casing itself; the other wire is led in an insulated state through the button 24 into the casing and is guided by the mechanisms of 80 the transmitter and of the receiver into the casing 10. The button 24 is provided with an insulating tube, similarly as the insulation-piece 18, and is also to be inserted into the watchcasing 10 and to be fastened by a screw. 85 A corresponding needle-point of the inner conductor comes thereby into contact with the insulated tube.

In the transmitter, Figs. 9 and 10, 25 is the electromagnet, 26 the bobbin and 27 the dia- 90 phragm.

The stationary junction - pieces provided in the telephonic wire plant for the use of pocket - telephones are illustrated in three different forms by the Figs. 11 to 21.

Figs. 11 to 16 represent in different views a first form of the stationary junction-device. The whole mechanism is arranged in the casing 7 on the backwall 28. 30 is an insulating plate, carrying in its middle upon a metal 100 support 41 three coöperating toothed-wheels 38, 32. The middle wheel 32 has a slotted, shell-shaped projection 31, into which the key 5 of the cable 4 can be introduced. By turning the key 5 the toothed-wheel 32 can 105 be turned at an angle of 90°. By means of the slit 49 and of the stop 48 the angle of rotation is limited.

Upon the two outside toothed-wheels 38 there are axes 37 of insulating material. 110 Upon each of these axes there are two elastic contact-tongues 36 firmly screwed on.

The two contact-tongues 36 of the upper toothed-wheel 38, Fig. 11, are connected by elastic slide contacts 34, 35 and by the terminal screws 45 each with one of the two wires 4' of the telephone wire plant. The screws 45 serve at the same time for fastening the plate 30 on the casing-backwall 28. The corresponding two contact-tongues 36 of the 115 lower toothed-wheel 38 are connected by the flexible wires 47, by the bow 46 and by the terminal screws 45 each with one of the remaining wires of the telephone wire plant. When the toothed-wheel 32 is turned by 120 means of the key 5 at an angle of 90° in the direction of the arrow, the toothed-wheels 38 and the axes 37 turn at the same time at the same angle, whereby the contact-tongues 36 go around into the position denoted by 125 130

dashes and points; in this position they press the four contact-tongues 39, corresponding to them, out of the position marked by fully drawn outlines into the position marked by dashes and points. The contact-tongues 39 are elastically fastened to vertical walls 33 consisting of insulating material and reach with projecting flaps 43 into suitable slits 42 of the walls 33. The walls 33 themselves are guided in the four slotted pillars 44 and fastened therein by means of small screws. When the contact-tongues 39 are pressed to the walls by the elastic contacts 36, the projections 43 come a little forward 15 out of the slits 42 and thus come into contact each with one of the four wires 4 of the insertion-key 5 turned into the position (Fig. 11) marked by dashes.

The construction of the insertion-key is 20 represented by Figs. 14 to 16. The four wires of the cable 4 pass through an insulating body 40 in the way shown by Fig. 6, and are connected with the insulated wires embedded in the key 5. These wires are in the 25 bit of the key 5 rectangularly bent over and led out at both sides of the bit. The points, at which the conductor-parts issue out of the narrow side of the bit, must exactly correspond in their height to the positions of the 30 contact-flaps 43.

29 is a closing-device for the purpose of attaching the casing 7 to the backwall 28.

By the present arrangement the advantage is gained, that the contact-pieces of the 35 apparatus usually being out of the reach of the insertion-hole 6 are protected against damages which might arise by misuse of the junction-device. Further the contact-pieces are all arranged in such a way, that they can 40 be easily transposed and made unserviceable for the insertion-keys used up to then. This transposition of the contacts is effected according to the present invention at the end of the subscription period for the purpose of 45 compelling the subscribers to exchange the insertion-keys of the pocket-telephones for new keys and to pay for the new subscription. To transpose the contacts it is only necessary to set the insulating plates 33 in 50 their guiding pillars 44 higher or deeper and to displace correspondingly the contact-tongues 36 on the axes 37. Then the wires 4 of the key-bit 5 no more fit to the contact-flaps 43, and it is necessary to use a new key 55 with another disposition of the wires 4 in the bit 5.

Another form of carrying out the stationary junction-device is represented by the Figs. 17-19. The same signs of reference 60 of the Figs. 11-16 and of the Figs. 17-19 represent the same apparatus-parts. In the present arrangement the toothed-wheel 32 pushes the two racks 50 in a straight line to and fro, which racks are laterally arranged 65 and guided in slits. At each of the two racks

50 there are two insulated contact bows 51, 52, which with the one ends elastically glide on the insulation plate 30 and with the other ends correspondingly bent up grasp into guiding slits 55 of the insulation-walls 70 33. The insulation walls 33 are fastened by means of the pillars 56 and of the sliders 57 to the plate 30.

When the toothed-wheel 32 is turned in the direction of the arrow, the extremities of 75 the bows 51, 52 slide over the contacts 45, 53 arranged on the plate 30. At the same time the bow-extremities 52 guided in the slits 55 arrive at the inner end of the slits 55 and protrude a little out of the same. The key 5 in 80 turning into the vertical position sets itself with its wires 4 against the projecting extremities of the bow 52. In this way the cable 4 of the pocket-telephone is connected with the four wires belonging to the telephonic wire plant and attached to the terminal screws 45. Figs. 17 and 18 show the contact-bows 51, 52 out of connection, Fig. 19 on the contrary shows them in connection with the insertion key 5. This arrangement 90 too affords protection of the contact-pieces against misuse and easily permits a transposition of the inner contacts for the purposes above referred to. To this end it is only necessary to alter the height of the insulation-walls 33 at the pillars 56. Thereby 95 the elastic extremities of the bows 51, 52 arrive at other positions as regards to their height and give no more contact with the keys used before. Finally Figs. 20 and 21 100 show a third form of carrying out the stationary junction-device.

According to the same in the casing 7 on the insulating plate 30 the insulating disk 60 is elastically pivoted by means of the middle 105 spiral pressure-spring 61 and of the pins 64 laterally provided at the disk 60, so that it is able to turn round. This disk is situated just beneath the key-hole 6 of the casing-lid 7 and carries in its middle a cavity, into 110 which the key 5 when inserted places its axis and thus it is guided. In the insulation-plates 30 there are arranged the four conductor-pillars 59, carrying contact-tongues 58 fastened by terminal screws. The pillars 115 59 are connected by means of the four conductor-bows 65 with four contact-buttons 63, which somewhat protrude out of the plate 30.

The turn-disk 60 carries four terminal 120 screws 66, which are connected above with the four conducting wires and below carry elastic contact-tongues 62. In the position of the key 5, Fig. 20, the contact tongues 62 are displaced with regard to the buttons 63. 125 To connect the pocket telephone with the telephonic wire plant, the key 5 is pressed into the casing 7, so that its bit comes behind the lid of the casing. Thereby the disk 60 is pressed down upon the backwall 30 of the 130

casing. Now the key is turned in the direction of the arrow, Fig. 21, at 90° and by means of the projection 67 carries the disk pressed down. The key is kept in its pressed down position by the casing-lid fitting behind the key-bit. When the disk 60 turns, the contact-tongues 62 arrive at the corresponding buttons 63. At the same time the conductor-parts 4 of the key-bit come into contact with the conductor-extremities 58. By this procedure the pocket-telephone is connected with the telephonic wire plant.

By a transposition of the conductor extremities 58 the stationary junction-device can be quickly made unserviceable for the keys used before.

The communication with the telephonic central station is effected with the present invention similarly as with other telephonic apparatuses. By the insertion of the key the central station receives the signal of a bell or of a lamp flashing up and mediates the desired conversation in the usual way.

As in the present case every one will have his own pocket-telephone which he is able to connect everywhere with the telephonic wire-plant, it is clear, that the use of the whole telephone plant will be facilitated and augmented by the introduction of the present invention. Besides it appears from the

stand-point of the hygiene and of the cleanliness a great step, that every one will possess a telephone used by himself alone and that one is not compelled to use an apparatus that is used jointly by many other people.

35

What I claim is:

1. The combination with a telephone and a key connected thereto and carrying the conductor terminals of said telephone, of station contact apparatus comprising movable contact parts operable by said key and stationary contact parts, said last named contact parts being connected to the wires of the telephone system.

2. The combination with a telephone and a key connected thereto and carrying conductor terminals, of telephone station apparatus having contact pieces, which in their position of repose lie out of the reach of the key and devices movable only by the key to put said contact pieces in communication with the latter, for the purpose of protecting the contact pieces against damage caused by misuse of the stationary junction apparatus.

In witness whereof, I subscribe my signature, in presence of two witnesses.

NUCHIM LEIB WEINGOTT.
